UNITED STATES PATENT OFFICE.

PAUL E. SCHLEICHER AND WALTER C. CALCOTT, OF GARY, INDIANA, ASSIGNEES TO SCHLEICHER, INC., OF GARY, INDIANA, A CORPORATION OF ILLINOIS.

DESIGN FOR A RADIATOR COVER OR SIMILAR ARTICLE.

Application filed December 23, 1927. Serial No. 24,610. Term of patent 3½ years.

To all whom it may concern:

Be it known that we, PAUL E. SCHLEICHER and WALTER C. CALCOTT, citizens of the United States, and residing in the city of Gary, in the county of Lake and State of Indiana, have invented a new, original, and ornamental Design for a Radiator Cover or Similar Article, of which the following is the specification, reference being had to the accompanying drawing, forming a part hereof.

The ornamentation shown on the drawing is continued over the entire panel.

On the drawings:

The figure illustrates a perspective view of the radiator cover showing our new design.

We claim:

The ornamental design for a radiator cover or similar article, as shown and described.

PAUL E. SCHLEICHER.
WALTER C. CALCOTT.
